UNITED STATES PATENT OFFICE.

ALBERT N. OTIS AND CARL L. IPSEN, OF SCHENECTADY, NEW YORK, ASSIGNEES TO
GENERAL ELECTRIC COMPANY, A CORPORATION OF NEW YORK.

ELECTRIC FURNACE.

Application filed September 10, 1925. Serial No. 55,585.

Our invention relates to electric furnaces or ovens employing resistance heaters or resistors, and has for its object the provision of an improved arrangement and construction which is particularly adapted for carrying out various heating operations.

Our invention has particular application in the heating of attenuated articles, such as mine drills, forgings, etc. In carrying out our invention we provide a plurality of relatively small furnace openings through which the parts to be heated may be inserted and arrange the heating resistor around these openings so as to be in close proximity to the work and radiate heat to the work from all directions. In one form of our invention we shape the resistor into a plurality of loops or convolutions substantially filling or coextensive with the heating chamber and provide openings through which the articles to be heated may be inserted between the convolutions.

For a more complete understanding of our invention reference should be had to the accompanying drawing in which Fig. 1 is a side elevation view of an electric furnace embodying our invention; Fig. 2 is a transverse vertical sectional view of the device shown in Fig. 1, while Figs. 3 and 4 are fragmentary enlarged views showing details of construction.

Referring to the drawing, the electric furnace in accordance with one form of our invention is provided with an elongated heating chamber which is defined by walls built up from heat refractory bricks 10, the whole being in a suitable metallic casing 11, and mounted on a suitable base 12. A plurality of relatively small openings 13 leading into the heating chamber are provided along one side, these openings being of the size suitable to permit the insertion of the article to be heated freely therethrough into the interior of the furnace chamber. As shown, the openings 13 may be defined by tubular heat refractory members 14 which are built into the side walls of the furnace, a suitable powdered heat refractory material 15 being provided around the outer ends of the tubes 14. A metallic plate 16 is mounted on the side of the furnace and provided with openings corresponding to the openings 13 of the furnace, these openings being countersunk as shown

at 17 on the inner side of the plate to receive the outer ends of the tubes 14 so as to support them.

At intervals along the tops of the side walls of the furnace specially constructed bricks are inserted provided with recesses 18 in which the ends of a plurality of transverse bars 19 of refractory electrically insulating material are laid whereby the bars are secured in place. In the furnace shown nine of these transverse bars are provided, and likewise nine openings 13 are provided. The bars 19 are arranged directly above the openings 13. At the bottom of the chamber specially formed bricks are likewise provided whereby two parallel grooves or troughs 20 and 21 are formed extending the full length of the heating chamber. These troughs are spaced somewhat from the sides of the chamber so that ledges 22 and 23 remain, a central ledge 24 being formed between the two grooves.

The furnace is heated by means of a ribbon shaped resistor which is draped or hung over the transverse rods 19 so as to hang downward in a series of V-shaped loops or convolutions between the rods, and laid in zigzag formation on the ledges 22, 23 and 24 at the bottom of the furnace. In the arrangement shown the resistor is divided into two sections 25 and 26, each section, consisting of a top or overhead series of loops and a bottom series of loops, extending the full length of the heating chamber. These two sections have their ends connected together in parallel relation and brought out at one end of the furnace to the terminals 27 and 28 whereby they may be connected in parallel to a suitable source of electrical supply. The two upper portions 25^a and 26^a are connected at one end to the terminal 28 and have their opposite ends connected respectively to the corresponding ends of the bottom portions 25^b and 26^b which extend the full length of the furnace and are connected to the terminal 27.

The bottom portions 25^b and 26^b are similar in shape to the top portions but are laid flatwise or horizontally on the ledges 22, 23 and 24, i. e., the bottom portions rest on their edges on these ledges. In the arrangement shown, the bottom portion 25^b extends back and forth between the ledges 22 and 24 with its bends resting on the ledges and the por-

tion 26^b rests in a similar manner on the ledges 23 and 24. The bottom portions are arranged also so that their bends occur in the same vertical transverse plane of the furnace, as shown in detail in Fig. 4, the zigzag lengths of the bottom portions being parallel. This arrangement provides for the maximum spacing of the bottom portions. In order to maintain this spacing and assure that the 10 bottom portions do not come in contact with each other, notches 29 are cut in the ledges 22, 23 and 24 in which the bends are laid. Preferably the front section 26 is made somewhat heavier so that its rate of heat generation 15 will be higher to compensate for the loss of heat through the openings 13.

With this arrangement of the heating resistor it will be observed that heat is radiated from all directions to the tools inserted 20 through the openings 13. This will be apparent from an examination of Fig. 3 in which a mine drill 30 is shown in the position relative to the heating resistor which it would have when inserted through one of 25 the openings 13. The depending loops 31 of the top portions of the two sections hang down between the opening 13, as shown in Fig. 1, so that the work pieces are inserted 30 between these loops, and between the top and bottom portions, so as to be brought in close 35 proximity to the heating resistor. It will be observed that the loops of the resistor substantially fill or are coextensive with the heating chamber, in fact the loops of the upper 40 portions alone substantially fill the chamber, the top and bottom portions being in close proximity to each other, and the work pieces being inserted, as previously noted between these portions and between the loops of the 45 top portion. The arrangement of the supports for the resistor, i. e., the bars 19 and the ledges 22, 23 and 24 are such that the resistor is supported with a very small area 50 of contact between the resistor and the supporting parts. This provides for efficient 55 radiation of heat from the resistor, preventing local overheating at the points of support. Furthermore, the horizontal arrangement of the lower portions allows the scale 60 to drop through into the troughs 20 and 21 without short-circuiting portions of the resistor. The particular arrangement shown 65 provides an exceedingly rugged and reliable construction.

55 In accordance with the provisions of the patent statutes we have described the principle of operation of our invention, together with the apparatus which we now consider to represent the best embodiment thereof, 60 but we desire to have it understood that the apparatus shown and described is only illustrative and that the invention may be carried out by other means.

What we claim as new and desire to secure 65 by Letters Patent of the United States is:—

1. An electric furnace comprising walls forming a heating chamber, a plurality of parallel bars extending across said chamber, having their ends secured in opposite walls, and a heating resistor hung from said bars 70 in a series of depending loops.

2. An electric furnace comprising side and end walls forming a heating chamber, a heating resistor in said chamber arranged in a plurality of loops extending lengthwise of 75 said chamber, said side walls being provided with a plurality of apertures through which the articles to be heated can be inserted between said loops.

3. An electric furnace for heating attenuated articles comprising side and end heat refractory walls forming a heating chamber, and a heating resistor in said chamber provided with a plurality of loops extending from one end of said chamber to the other, 85 one of said side walls being provided with a plurality of apertures through which the articles to be heated can be inserted between said loops.

4. An electric furnace for heating attenuated members comprising heat refractory walls forming an elongated furnace chamber provided with a plurality of relatively small side openings, and a heating resistor extending lengthwise of said chamber arranged in 95 a plurality of loops hanging between said openings.

5. An electric furnace comprising heat refractory walls forming an elongated furnace chamber provided with a plurality of relatively small side openings, a heating resistor extending lengthwise of said chamber arranged in a plurality of loops hanging between said openings, a plurality of bars extending across said chamber forming supports for said resistor, and a sinuous resistor on the bottom of said chamber below said openings, said resistors being arranged in said chamber for direct radiation to the work inserted through said apertures. 110

6. An electric furnace comprising side and end heat refractory walls forming a furnace chamber, one of said side walls being provided with a plurality of relatively small openings, a plurality of insulating bars extending across said chamber from side to side thereof, and a heating resistor hanging from said bars in a series of loops arranged between said opening. 115

7. An electric furnace comprising side and end heat refractory walls forming a heating chamber, a resistor shaped into a series of vertical loops and a series of horizontal loops extending from one end of the chamber to the other, said side walls being provided with 125 apertures through which the articles to be heated can be inserted between said series of vertical and horizontal loops and between said vertical loops.

8. An electric furnace comprising heat re- 130

fractory walls forming an elongated heating chamber provided with a plurality of relatively small side openings, a plurality of bars of insulating material extending across the top of said chamber, spaced ledges on the bottom of said chamber extending lengthwise thereof, and a sinuous heating resistor extending lengthwise of said chamber supported on said bars and ledges.

In witness whereof we have hereunto set ¹⁰ our hands this 9th day of September, 1925.

ALBERT N. OTIS.
CARL L. IPSEN.
